CLAIM

The ornamental design for a handheld steamer as shown and described.

DESCRIPTION

FIG. 1 is a perspective view of an embodiment of a handheld steamer showing our new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top view thereof;

FIG. 7 is a bottom view thereof;

FIG. 8 is a perspective view of another embodiment of a handheld steamer showing our new design;

FIG. 9 is a front elevational view thereof;

FIG. 10 is a back elevational view thereof;

FIG. 11 is a right side elevational view thereof;

FIG. 12 is a left side elevational view thereof;

FIG. 13 is a top view thereof; and,

FIG. 14 is a bottom view thereof.

The even dash lines appearing in the figure drawings depict portions of the handheld steamer that form no part of the claimed design.
